US0D1045897S

(12) **United States Design Patent** (10) Patent No.: **US D1,045,897 S**
(45) Date of Patent: ** Oct. 8, 2024

(54) **AUTOMOBILE DISPLAY SCREEN WITH GRAPHICAL USER INTERFACE SHOWING POWER GAUGE**

(71) Applicant: **Atieva, Inc.**, Newark, CA (US)

(72) Inventors: **Nicholas James Hope**, Oakland, CA (US); **Colin Sebestyen**, San Francisco, CA (US); **Derek N. Jenkins**, Malibu, CA (US)

(73) Assignee: **Atieva, Inc.**, Newark, CA (US)

(**) Term: **15 Years**

(21) Appl. No.: **29/850,110**

(22) Filed: **Aug. 17, 2022**

(51) LOC (14) Cl. **14-04**

(52) U.S. Cl.

USPC **D14/485**

(58) **Field of Classification Search**

CLAIM

We claim the ornamental design for an automobile display screen with graphical user interface showing power gauge, as shown and described.

DESCRIPTION

The FIGURE is a front view of an automobile display screen with graphical user interface showing power gauge, of the new design.

The outermost broken line rectangle shows the display screen, and forms no part of the claimed design.

1 Claim, 1 Drawing Sheet

LAUNCH MODE
ACTIVATED
